(57) **CLAIM**

The ornamental design for a removable lid and associated container, as shown and described.

DESCRIPTION

FIG. 1 shows an isometric view of the removable lid and associated container.

FIG. 2 shows a front side view of the removable lid and associated container.

FIG. 3 shows a left side view of the removable lid and associated container; and,

FIG. 4 shows a top view of the removable lid and associated container.

The broken lines in the drawings depict environmental subject matter only and form no part of the claimed design.
